UNITED STATES PATENT OFFICE

ADOLPH PEDERSEN, OF CLEVELAND, OHIO, ASSIGNOR TO THE VANDORN-ELLIOTT ELECTRIC CO., OF CLEVELAND, OHIO, A CORPORATION OF OHIO.

ELECTRICALLY-OPERATED PORTABLE DRILL.

No. 809,394.

Specification of Letters Patent.

Patented Jan. 9, 1906.

Application filed September 19, 1904. Serial No. 224,953.

To all whom it may concern:

Be it known that I, ADOLPH PEDERSEN, a citizen of the United States, and a resident of Cleveland, county of Cuyahoga, and State of Ohio, have invented a new and useful Improvement in Electrically-Operated Portable Drills, of which the following is a specification, the principle of the invention being herein explained and the best mode in which 5 I have contemplated applying that principle, so as to distinguish it from other inventions.

My invention relates to portable drills, and particularly to electrically-operated portable drills, its object being to provide a machine 15 of said aforesigned character which will embody economy in construction and operation and safety in manipulation.

The said invention consists of means hereinafter fully described, and particularly set 20 forth in the claims.

The annexed drawings and the following description set forth in detail certain mechanism embodying the invention, such disclosed means constituting but one of various 25 mechanical forms in which the principle of the invention may be used.

In said annexed drawings, Figure 1 represents a vertical axial section of an electrically-operated portable drill embodying my 30 invention, the drill-spindle being shown therein in elevation and the shank of the drill being shown located in such spindle. Fig. 2 represents a plan view of said structure, showing the top cap or head removed, the operating-handles being shown as broken away. Fig. 3 represents a detailed side elevation of 35 that portion of the device embodying the controlling-handle and the electrical controller and safety mechanism governing the action of the motor. Fig. 4 represents a plan 40 of the removable end cap or head of the casing inclosing the mechanism of the drill. Fig. 5 represents a cross-sectional view of said head, taken upon the plane indicated by 45 line V V of Fig. 4.

My improved construction embodies an outer casing A, made of magnetic material, such as cast-steel, comprising a main portion a, a lower end cap or shell a', permanently attached to the main portion a, an upper removable head a², and a lateral removable portion a³, inclosing and carrying the controller and safety devices previously men-

tioned. This portion a³ is provided with an integral projection a⁴, whose inner surface 55 forms a bearing for the operating-handle B. Diametrically opposite the projection a⁴ and formed integral with the main portion a of the casing is a second projection a⁵, into which is screwed a second handle B', the latter being immovably secured to said projection. As shown in the drawings, the axes of these handles B B' lie in the same straight line. The lower portion a' of the casing is provided with a hollow centrally-located portion a⁶, in which is secured a bushing a⁷, forming a bearing for the drill-spindle C. This spindle projects upwardly into the casing and is formed with a collar c intermediate of the ends of the spindle, the upper or 65 inner end of the latter being of reduced diameter, as shown. Upon the spindle intermediate of the flange c and the bushing a⁷ is keyed a spur-gear D, which meshes with two pinions d d, located diametrically opposite each other within the casing, as shown in Fig. 1. These pinions are secured to the lower ends of two short pintles e e, which are journaled in vertical bearings f f, formed in a transversely-located diaphragm F, which 70 is secured between the upper casing portion a and the lower casing portion a', as shown in said figure. To the upper ends of these pintles are respectively secured two gears e' e', which mesh with the pinion E, 75 keyed to the lower end of the hollow motor-shaft G. The lower end of this shaft is provided with a cone g, which bears upon anti-friction-balls g', the latter traveling in a raceway f', secured in a suitable seat f², 80 formed in the central part of the diaphragm F. The upper end of the motor-shaft is provided with a cone g², bearing upon anti-friction-balls g³, which travel in the raceway a¹⁷, secured to the central part of the removable 85 head a². Coaxial with and located within the hollow shaft G is a feed-screw H, comprising a male member H' and a female member H², the latter projecting through a central opening a⁸, formed in the center of the removable head a², the upper end of said member being provided with a handle h and a conical centering-piece h'. The lower end of said male member H' projects below the lower end of the shaft G and is formed with 90 an end bearing h² for receiving the upper end 95

of the drill-spindle C. Secured to the lower end of this member H' is a ball-race member h³. Disposed opposite said member and secured to the drill-spindle is a second race member c', the two members forming a race-way for a series of antifriction-balls c². The member c' is seated so as to bear against the flange e, previously referred to, as shown clearly in Fig. 1. It will thus be seen that an antifriction thrust-bearing is formed for receiving the thrust due to the feeding action of the feed-screw when the device is in operation. Secured to the central portion of the shaft G is the armature G' of a multipolar series-wound constant-potential electric motor, the poles being four in number in the device illustrated. The pole-pieces G² of the field structure surrounding the armature are secured to the inside of the casing by means of screws a⁹.

The removable head a² is provided with four bolt-holes a¹⁰, located ninety degrees from each other, through which extend binding-bolts J, whose inner and outer ends are threaded, the inner ends extending through the diaphragm F. These bolts pass through the casing between the field-sections, as shown in Fig. 2, and are provided with nuts at their respective ends which engage the diaphragm and removable head, respectively, as shown in Fig. 1, thereby securely fastening the head in place, as will be readily understood. Wound upon each bolt is a resistance-coil K, such coils forming a series of resistances properly connected with a controller-arm and contacts hereinafter described, whereby such coils may be thrown into and out of the circuit to vary the speed of the motor, as will be readily understood. This arrangement of resistance-coils, it will be seen, is very convenient and compact and does not necessitate the provision of a separate compartment or space for the necessary resistance. This feature of construction adds materially to the economy of the arrangement and construction of the mechanism. Secured to the head a² in any suitable manner so as to project from the inner surface thereof are two studs a¹¹ a¹¹, upon the inner ends of which are respectively secured brush-holders a¹² a¹². That portion of the head to which the studs are secured consists of a ring a¹³, provided with an inner circular boss seated in a circular aperture a¹⁴, formed in the main portion 55 of the head a². The said ring a¹³ is provided with a series of elongated segmental slots a¹⁵, through which pass binding-screws a¹⁶, by means of which the ring may be fixed relatively to the main portion of the head. By 60 means of this construction it will be seen that the ring, and hence the brush-holders, may be caused to assume various positions around the line of the motor-axis and that variations in the adjustment of the brushes upon the 65 commutator G³ of the motor may be effected.

This commutator is secured upon the motor-shaft in the usual manner and as illustrated in Fig. 1.

As before described, the operating-handle B is rotatably mounted upon the casing portion a³. The inner end of said handle projects into said casing portion and is of a reduced diameter, as shown in Fig. 1. Between the extremities of this reduced portion is loosely mounted a disk b, provided with an aperture b'. Below this disk b is rotatably secured to said reduced portion a second disk b², which is similarly provided with an aperture b³. Secured to the inside of disk b² is a spring member b⁴, provided with a stud b⁵, which normally projects through the aperture b³ and a short distance into the aperture b'. It will therefore be seen that when the parts are in this described position the disk b is rotatably secured to the handle B, so as to turn therewith and with the disk b². A spiral spring b⁶ (shown in dotted lines in Fig. 3) is secured to the disk b, and fixed to the latter is a contact-segment b⁷, which is adapted to contact one or more of a series of contacts k, (shown in dotted lines in Fig. 3 and in full lines in Fig. 2,) the latter being suitably connected with the resistance-coils in the manner usually employed in the construction of controllers. The spring b⁶ is so arranged that when the pin b⁵ is out of engagement with the aperture b' said disk b will be moved by spring b⁶ so as to cause the contact-segment b⁷ to disengage the contacts k—that is, cause said segment to assume its "off" position, in which no current is permitted to flow through the motor-circuit. Passing through the main casing portion a and screwed into the pole-piece G² adjacent to the casing portion a³ and having its outer surface lying in proximity to the path of travel of the spring member b⁴ is an iron member M. Such construction, it will be observed, will render this member M magnetic when the pole-pieces G² are magnetized by the flow of current through the motor-field. Secured to the handle B and rotatable therewith is a member N, formed with a bottom flange n, having formed in its periphery a notch n', the latter being cut upon the arc of a circle. Adjacent to said member is a manually-operated switch O, arranged to reverse the current through the motor. This switch is provided with a circular flange o, in which is cut two notches o' o', the latter being cut upon the arc of a circle substantially equal to that defined by the circumference of the flange n of the member N. The arc upon which the notch n' is cut is that of a circle substantially defined by the circumference of the flange o of the switch. The location of the notch n' is such that when the controller is in its off position said notch will be located opposite the flange o. It will therefore be seen that when these parts occupy such last-described position the 130

reversing-switch may be operated and that when the controller contact-segment is in a position such as to permit current to flow through the motor the reversing-switch can-
5 not be operated and is locked in place. This prevents the reversal of the current while flowing, and thus prevents damage to the electrical mechanism.

The above-described mechanism operates
10 as follows: Current being sent through the motor by turning on the controller contact-segment, the armature of the motor revolves, thus revolving the pinion E and gears e' e', pinions d d', and gear D, and hence the spindle
15 C. The spring member b⁴ is caused to be of a strength such that when the magnetic flux of the motor reaches a certain predetermined degree or amount the magnetic field surrounding the magnetic member M will overcome
20 the resistance of the spring member, attract same toward member M, and thus release the disk b from its engagement with the handle, and thus allow such disk to be operated by the retractile spring b⁶, so as to throw the contact-segment of the controller into its off position.
25 My invention is so designed that such actuation of the controller to its off position will take place when the resistance to the drilling operation becomes so great that
30 there is effected a flow of current through the motor which is slightly less than the amount which would be injurious to the mechanism. The current is therefore automatically shut off at the proper moment to prevent damage, and neither an inexperienced, careless, nor malicious operative can in any way hold or force the drill to the work over and above its adjusted capacity.

Having described my invention in detail,
40 that which I particularly point out and distinctly claim is—

1. In a portable electrically-operated drill, the combination of a multipolar motor provided with a casing and a hollow shaft; a drill-
45 spindle mounted in said casing; intermediate gearing connecting said motor-shaft and spindle; and a feed-screw located within said hollow shaft and provided with an end portion projecting therefrom and having a bearing
50 adapted to receive the inner end of said drill-spindle.

2. In a portable electrically-operated drill, the combination of a multipolar motor provided with a casing and mounted within the
55 latter and having a hollow shaft; a feed-screw mounted within said shaft and coaxial therewith; a drill-spindle mounted in one end of the casing and having its axis in the same straight line with the motor's axis; a removable head secured to the other end of said cas-

ing; intermediate gearing connecting said motor and spindle; a diaphragm located transversely of said line of the motor-axis, one end of said motor-shaft being supported by said head and the other by said dia-
65 phragm; and binding-bolts passing through said head between the separate field-sections and having their inner ends secured to said diaphragm.

3. In a portable electrically-operated drill, 70 the combination of a multipolar motor provided with a casing and mounted within the latter and having a hollow shaft; a feed-screw mounted within and coaxial with said shaft; a drill-spindle mounted in one end of 75 the casing and having its axis in the same straight line with the motor's axis; a removable head secured to the other end of said casing; intermediate gearing connecting said motor and spindle; a diaphragm located 80 transversely of said line of the motor-axis, one end of said shaft being supported by said head and the other by said diaphragm; binding-bolts passing through said head and between the separate field-sections and having 85 their inner ends secured to said diaphragm; and a controller for said motor having its resistance-coils mounted upon said binding-bolts.

4. In a portable electrically-operated drill, 90 the combination of a multipolar motor provided with a casing and a shaft; a drill-spindle mounted in said casing; a removable head secured to said casing, provided with a bearing for one end of the motor-shaft, and including an annular ring adjustable around the axis of the motor-shaft; brush-holders mounted upon said ring; intermediate gearing connecting said motor and spindle; a dia-
95 phragm located transversely of the motor-shaft and providing a bearing for the other end of the latter; and binding-bolts passing through said head between the separate field-sections and having their inner ends secured to said diaphragm. 100

5. In a portable electrically-operated drill, the combination of a motor provided with a casing and a shaft; a drill-spindle mounted in said casing; gearing connecting said motor-shaft and drill-spindle; and a feed-screw located within said casing centrally relatively to said motor and arranged with one end in juxtaposition to the inner end of said drill-spindle. 110

Signed by me this 14th day of September, 115
1904.

ADOLPH PEDERSEN.
